UNITED STATES PATENT OFFICE.

HAMLIN F. BILLMEYER, OF MILTON, PENNSYLVANIA.

TRIMMING-MACHINE.

SPECIFICATION forming part of Letters Patent No. 373,960, dated November 29, 1887.

Application filed June 24, 1887. Serial No. 242,407. (No model.)

To all whom it may concern:

Be it known that I, HAMLIN F. BILLMEYER, a citizen of the United States, residing at Milton, in the county of Northumberland and State of Pennsylvania, have invented a new and useful Improvement in Trimming-Machines, of which the following is a specification.

My invention relates to an improvement in machines for trimming the tenons of door, shutter, and blind rails; and it consists in the peculiar construction and combination of devices, that will be more fully set forth hereinafter, and particularly pointed out in the claims.

In the drawings, Figure 1 is a front elevation of a machine embodying my improvements. Fig. 2 is a rear elevation of the same. Fig. 3 is an end elevation. Fig. 4 is a vertical sectional view taken on the line $x-x$ of Fig. 1. Fig. 5 is a detail perspective view of one of the cutting-bits.

A represents a vertical frame of suitable height. This frame is provided in its sides with vertical grooves B.

C represents a sliding frame comprising a pair of brackets, D, having vertical tongues on their inner sides to enter the grooves B, a front bar, E, connecting the front upper sides of the brackets, and a cross-board, F, connecting the rear sides of the brackets and extending across the rear side of the vertical frame. On the vertically-movable frame C is secured a bed-plate, G, which is arranged horizontally and projects beyond one side of the main frame and has on its rear side a vertical flange, H. On

the rear side of the cross-board F is a projecting block, I. K represents a similar block, which is secured on the rear side of the frame A, near the upper end thereof. A vertical elevating-screw shaft, L, is swiveled in the upper block, K, and extends down through a threaded opening in the block I. By turning this screw-shaft it will be understood that the bed on the front side of the main frame may be raised or lowered.

M represents a crank-handle having a socket adapted to fit the upper end of the screw-shaft.

N represents a horizontal gage, which is secured on the front side of the frame A. The ends of the said gage project beyond the sides of the main frame. On one end of the said gage is secured a sliding sleeve or stop, O, and the said sleeve or stop is provided with a set-

screw, P, adapted to bear against the gage and thereby secure the sleeve or stop thereto at any desired longitudinal adjustment.

55

R represents a right-angled bracket-plate, the lower side of which bears against the upper side of the gage N, and the upper side of the said bracket-plate is provided with a vertical slot, through which extends a set-screw, S, that enters a threaded opening in the front side of the frame A and clamps the bracket-plate to the latter.

T represents a horizontal cutting-bit, which projects from the front side of the frame A and rests upon the upper side of the gage N.

55

U represents a vertically-movable head, which is secured in a vertical slot, V, made in the upper portion of the frame A, and the said head is adapted to travel in the said slot. A coiled spring, W, is concealed in a vertical opening made in the frame A and communicating with the lower end of the slot V. This coiled spring bears against the under side of the head U, and the function thereof is to normally raise the said head. To one side of the latter, and projecting from the front side of the frame A and at right angles thereto, is a cutting-bit, X, which is adapted to move vertically with the head U.

75

Y represents a treadle, which is fulcrumed to the floor at a slight distance to one side of the frame A. The said treadle is connected to the head U by a rod, Z, and thereby the head may be caused to descend by placing one foot on the treadle.

80

The operation of my invention is as follows: The rail to be trimmed is fed from the tenoning-machine (not shown) onto the bed G, which has previously been elevated to the required height, so as to bring the upper edge of the rail flush with the upper side of the gage N. The rail is moved longitudinally on the bed G, and the upper edge of its tenon comes in contact with the horizontal bit T and is shaved and trimmed by the latter. The sleeve or stop O is adjusted longitudinally on the gage N, according to the depth of the tenon, and when the end of the tenon reaches the said stop or sleeve the motion of the rail is arrested, and the operator then causes the head U to descend, and thereby the vertical bit X makes a cut at the shoulder of the tenon and severs the shaving therefrom, thus completing

90

95

100

the operation of trimming that side of the tenon.

Having thus described my invention, I claim—

5 1. The combination, in a machine for trimming tenons, of the bed-plate G, the horizontal bit T, the gage N, the stop O, adjustable longitudinally on the said gage toward and from the bit T, and the vertically-movable head U, carrying the vertical bit X, all combined and arranged to operate substantially as described.

15 2. In a machine for trimming tenons, the combination of the vertical frame A, the vertically-adjustable bed projecting from one side of the frame, the gage N, arranged parallel with the bed and above the same, the horizontal cutting-bit T, projecting from the frontside of the frame and resting on the edge of the gage, the longitudinally-adjustable stop O on 20 the gage, and the vertically-movable head U, having the vertical bit X, substantially as described.

25 3. The combination of the vertical frame A, the vertically-adjustable bed secured to the said frame, the elevating-screw to raise and lower the bed, the gage N, arranged horizontally on the frame A, the horizontal bit T, projecting from the frontside of the frame and resting on the gage, the sleeve or stop O on the 30 gage and adjustable longitudinally on the gage, the vertically-movable head U, having the vertical bit X, the spring to normally raise the said head, and the treadle connected to the head to lower the same, for the purpose set 35 forth, substantially as described.

4. In a machine for trimming tenons, the combination of the frame having the horizontal stationary bit T and the vertically-movable head having the vertical cutting-bit X, substantially as described.

40 5. In a machine for trimming tenons, the combination of the frame having the horizontal stationary shaving-bit T, the vertically-movable head having the vertical cutting-bit X, the lever to depress the head, and the spring 45 to raise the same, substantially as described.

6. In a machine for trimming tenons, the combination of the frame having the stationary horizontal shaving-bit T, the horizontal gage N, bearing under the said bit, said gage 50 being stationary, the vertically-movable head W above the bit T and having the vertical cutting-bit X, and the bed G, vertically adjustable with relation to the bit, substantially as described.

55 7. In a machine for trimming tenons, the combination of the vertically-movable head carrying the vertical cutting-bit X and the horizontal stationary shaving-bit T at the lower limit of the path of the head, substantially as 60 described.

In testimony that I claim the foregoing as my own I have hereto affixed my signature in presence of two witnesses.

HAMLIN F. BILLMEYER.
